UNITED STATES PATENT OFFICE.

WILLIAM M. DANA AND CHARLES C. PALMER, OF MINNEAPOLIS, MINNESOTA; SAID
PALMER ASSIGNEE TO SAID DANA.

ITEM-ALARM.

1,296,270.

Specification of Letters Patent. Patented Mar. 4, 1919.

Application filed March 4, 1918. Serial No. 220,197.

To all whom it may concern:

Be it known that we, WILLIAM M. DANA and CHARLES C. PALMER, citizens of the United States, residing at Minneapolis, in the county of Hennepin and State of Minnesota, have invented certain new and useful Improvements in Fire-Alarms; and we do hereby declare the following to be a full, clear, and exact description of the invention, such as will enable others skilled in the art to which it appertains to make and use the same.

This invention has for its object to provide an improved fire detector and alarm especially adapted for use in connection with telephone systems; and to such ends, the invention consists of the novel devices and combinations of devices hereinafter described and defined in the claims.

20 In the accompanying drawings which illustrate the invention, like characters indicate like parts throughout the several views.

Referring to the drawings,

Figure 1 is a diagrammatic view illustrating the complete system; and

Fig. 2 is a detail showing one of the automatic detectors in the form of a thermally actuated circuit closer having a fusible element.

30 Located in the building in which the detecting alarm system is installed, is an electric circuit herein designated as the detector circuit 3, in which is a source of electrical energy, such as a storage battery 4. This detector circuit 3 has a closer, to wit any desired number of branch line leads 3^a that are normally open, but at numerous places, are adapted to be cross connected by thermally actuated circuit closers of suitable 35 form. These thermally actuated circuit closers may take various forms, but as shown, are made up of approximately U-shaped springs 4 normally connected on one side to one of the pair of leads 3^a, but normally out 40 of engagement with contacts 5 on the other lead. The prongs of these circuit closers 4 are normally connected by solder 6 of low fusibility, that is, of fusibility thought desirable to cause the same to properly melt 45 before a fire has done much damage in the vicinity thereof. When the solder 6 melts, the loosened prong of the contact closer 4 will spring into engagement with the co-operating contact 5 and close the detector

circuit, thereby causing certain operations 55 presently to be described.

The several pairs of branch leads 3^a may be assumed to extend to different floors of the building and they are, of course, extended to such places on the several floors 60 and provided with the fire detecting circuit closers wherever deemed advisable. Of course the closing of the circuit through any one of these circuit closers, produced by an abnormally high temperature induced by an 65 incipient fire, will cause the closing of the detector circuit.

Located preferably in the office of the building but at any other suitable place and connected in the detector circuit 3 is an electromagnet 7, which, when energized, operates on the armature end of a drop latch 8 that is suitably pivoted at 9. At the free end of its long arm, the latch 8 is provided with a hook or detaining lock 10 that normally holds the upper end of a small intermediate pivoted switch actuating lever 11 that is under tension to move from a suitably anchored coiled tension spring 12. Also, located in one lead of the detector circuit 70 is a pair of spring contacts 13 that are under spring strain to separate and, when released, open the said detector circuit. However, normally, or when the lever 11 is held by the latch 8, the lower end of said 75 lever presses the free ends of the contacts 13 into engagement and closes the detector circuit at that point. The lever 11, electromagnet and latch described, constitute one 80 form of an important device for this system which may be designated as an electromagnetic switch actuator.

Located also in the building in which the signal system is installed, and preferably in the immediate vicinity of the electromagnetic switch actuator, is an alarm device 95 preferably in the form of an electrically actuated alarm bell 14. Located immediately adjacent to the local alarm bell 14 is a telephone transmitter 15. The bell 14 and a 100 battery 16 are connected in a local alarm circuit 17, the leads of which are connected to a pair of spring contacts 18 that are insulated from each other and normally fixed so the said circuit is normally open. The transmitter 15 and a battery 19 are connected in one of a pair of leads 20 that are connected across the telephone line 21. The leads 20

terminate in spring contacts 22 that are insulated from each other and normally separated so that the circuit 20, at the said contacts is normally open.

5 The telephone line 21 may be of the usual construction and arrangement and may be assumed to be a private line connecting the office telephone of the building in which the system is installed, with the customary central connections, such as the usual receiver 23 and call lamp 24, there being a switch 25 by which either the receiver 23 or call lamp 24 can be connected in the line circuit.

10 The free ends of the two sets of spring contacts 18 and 22 of circuits 17 and 20, respectively, are separated but located quite close together, so that one member of each of said pair of contacts is adapted to be engaged by a presser block 26 of insulating material carried by the circuit closing lever 11 already described.

15 The numeral 27 indicates an electric gong or bell assumed to be located in a convenient place outside of the building in which the system is installed, and the numeral 28 indicates a central electric gong which may be assumed to be located in the dwelling or home of the person owning the building in which the alarm system is installed. The bell 27 is shown as connected across the alarm circuit 17 by leads 29, and the bell 28 is shown as connected across the leads 29 by branch leads 30.

20 With this arrangement, as is evident, when the contacts 18 are pressed together, alarm circuit 17 will be closed, thereby operating a local alarm bell 14, and the closing of this alarm circuit simultaneously closes the circuit through the outside alarm bell 27 and the owner's private alarm bell 28. Moreover, when the spring contacts 22 are pressed together, the circuit through the local alarm transmitter 15 will be closed so that if central then cuts in her receiver, she can hear the alarm given by the local alarm bell 14.

25 The operation of the fire detector and alarm system summarized, is substantially as follows:

30 Whenever a fire in a building in which the system is installed, creates such abnormal heat as to melt the fusible material 6 of any one of the circuit closers 4, the detector circuit 3 will be closed and magnet 7 will be energized. When magnet 7 is energized it operates on the depending armature end of the latch 8 and lifts the same, thereby releasing switch closing lever 11. When switch closing lever 11 is released, spring 12 will throw the insulating presser block 26 against the free ends of the adjacent spring contacts 18 and 22, thereby closing alarm circuit 17 and its branch circuits 29 and 30 and simultaneously therewith, closing a transmitter circuit 20 through the main line. Normally, a central switch 25 is in position to cause the

35 closing of the line circuit through call lamp 24. Hence, the instant that the detector circuit is closed and alarm bells are set into action, central's call light 24 will be illuminated just the same as if a call was being sent in. Central then moves over switch 25 to cut in her receiver 23 and she will then hear the sound made by the local alarm bell 14, which sound is taken up and transmitted by the special transmitter 15. Central will, of course, understand that the ringing of this bell at the particular building or place where the system is installed, indicates that a fire has started and, hence, will call the fire department, directing them to the place of the fire. At the same time, the owner or manager or other party especially interested in the building or plant, by the ringing of the alarm bell 28, will be notified that a fire has started.

40 The call lamp 24 is only one of several forms of call device that may be used to call the attention of central to the fact that a fire has started. A bell may be used as an addition to or substitute for the said lamp when desired. It should now be noted that when the detector circuit 3 is closed, as above described, and magnet 7 energized and caused to act upon latch 8 to release switch closing lever 11, as above described, the initial movements of the said lever 11 serve to release the one spring contact 18 from the other, thereby permitting the said spring contacts to be separated and open the detector circuit immediately after the circuit closing lever has been released. This is important because it cuts out the battery 4 immediately after it has performed its office of effecting release of the circuit closing lever and the closing of the alarm and special transmitter circuits.

45 What we claim is:

1. A fire detecting and alarm system comprising a detecting circuit having therein a multiplicity of normally open thermally actuated circuit closers, an alarm circuit having therein an alarm device and a normally open switch, and an electromagnetic switch actuator whereby, when said detector circuit is closed, the switch of said alarm circuit will be closed, said detector circuit having a normally closed switch arranged to be opened by the switch closing movement of said switch actuator.

50 2. A fire detecting and alarm system comprising a detecting circuit having therein a multiplicity of normally open thermally actuated circuit closers, an alarm circuit having therein an alarm device and a normally open switch, an electro-magnetic switch actuator whereby, when said detector circuit is closed, the switch of said alarm circuit will be closed, a line circuit, a transmitter connected therein and located in close proximity to the alarm device of said alarm circuit, and

- 5 a normally open switch in said transmitter circuit connections, said latter switch also being arranged to be closed by said switch actuator when said detector circuit is closed, 45
 5 said detector circuit having a normally closed switch arranged to be opened by the switch closing movement of said switch actuator.
- 10 3. A fire detecting and alarm system comprising a detecting circuit having therein a multiplicity of normally open thermally actuated circuit closers, an alarm circuit having therein an alarm device and a normally open switch, an electro-magnetic switch actuator whereby, when said detector circuit is closed, the switch of said alarm circuit will be closed, said detector circuit having a normally closed switch arranged to be opened by the switch closing movement of said 50
 15 switch actuator, a line circuit which, at the central station has a telephone receiver, a central call device, and a switch cutting said receiver and call device into and out of action at will.
- 20 25 4. A fire detecting and alarm system comprising a detecting circuit having therein a multiplicity of normally open thermally actuated circuit closers, an alarm circuit having therein an alarm device and a normally open switch, an electro-magnetic switch actuator whereby, when said detector circuit is closed, the switch of said alarm circuit will be closed, said detector circuit having a normally closed switch arranged to be opened by the switch closing movement of said 55
 25 switch actuator, a line circuit which, at the central station has a telephone receiver, a central call device, and a switch cutting said receiver and call device into and out of action at will.
- 30 35 5. In a fire detecting and alarm system, the combination with a detecting circuit including an electromagnet and a multiplicity of normally opened thermally actuated cir- 60
